UNITED STATES PATENT OFFICE.

PERRY FRANKEL, OF PHILADELPHIA, PENNSYLVANIA.

DESIGN FOR A BORDER FOR LACE EDGING.

45,867.

Specification for Design.

Patented June 2, 1914.

Application filed March 25, 1914. Serial No. 827,241. Term of patent 7 years.

To all whom it may concern:

Be it known that I, PERRY FRANKEL, a citizen of the United States, residing in Philadelphia, Pennsylvania, have invented a new, original, and ornamental Design for Borders for Lace Edging, of which the following is a specification.

Lace edgings and particularly those which are used as a trimming for ladies' underwear usually include a body portion or heading and an ornamental tip or border. The body portion or heading usually consists either of a closely knitted portion or of one having openings through which ribbon may be in-

serted. The border, embodying my invention, may be used in connection with any form of heading or it may be used independently.

The figure in the drawing is a face view of the border for lace edging embodying my new design.

I claim:

The ornamental design for a border for lace edging substantially as shown.

PERRY FRANKEL.
